UNITED STATES PATENT OFFICE.

WILLIAM CHARLES SPROESSER, OF BLOOMFIELD, NEW JERSEY, ASSIGNOR TO WEST-
INGHOUSE LAMP COMPANY, A CORPORATION OF PENNSYLVANIA.

INCANDESCENT ELECTRIC LAMP.

No Drawing.

Application filed December 3, 1921. Serial No. 519,764.

My invention relates to electrical devices employing incandescent metallic filaments, and more particularly it relates to electric incandescent lamps.

- 5 In the manufacture of incandescent lamps employing filaments of a refractory material, such as tungsten and the like, it is customary, in one stage of the process through which these lamps are carried in 10 the course of their fabrication, to pass an electrical current through the filament. This operation, known in the art as flashing, is always practiced after the lamp has been exhausted and permanently sealed-off, and 15 one of its objects is to vaporize a material, which is commonly termed a getter and which has been placed within the lamp, preferably on the filament. The function of the getter substance is well known to 20 those versed in the art and various theories have been advanced by skilled artisans concerning its action in assisting the lamp in properly functioning. It may be stated, however, with reference to the getter, that 25 its principal uses are confined to the elimination of the dark deposit of filamentary material upon the inner walls of the envelope, which affects the candle-power maintenance value of the lamp, and also that it 30 serves to overcome the harmful effects of the residual gases remaining within the lamp after exhausting and which are due to poor exhaust or to occluded gases which come off at some period subsequent to that 35 operation.

- The theories which have been offered in explanation of the getter action, as well as the literature relating to such substances, do not mention utilizing the getter in a manner which will improve the strength of the filamentary structure, after flashing, over that which it normally would have if the customary flashing schedules were followed and well-known getter materials were employed.

- 40 That it is very desirable to increase the present strength of the lamp filaments after flashing is evident when it is considered that a shrinkage occurs in the factory and during shipment of about five-tenths of one percent of the total output. This shrinkage has been directly traced to the weakened condition of the filaments resulting from 45 improper crystal growth during flashing.

In order to avert such losses, I have sought 55 to improve the strength of the lamp filament to such an extent that the usual shocks which a lamp may be subjected to in transit will be insufficient to cause its breakage. It is, therefore, an object of my invention to 60 improve the strength of filaments over that which is normally obtained when present methods are practiced.

Many lamp failures also occur during the course of manufacturing the lamp, particularly during the flashing operation, which may be attributed to arcs which form across the leading-in wires and filament sections. These arcs frequently melt down the leading-in wires and filaments and thus render 70 the lamp worthless. It is believed that the formation of these arcs may be induced by the ionization of the residual gases within the envelope resulting from poor exhaust; or else may be aided by the favorable medium afforded the current by the vaporizing getter material; or it may even be that the combination of these actions may be the cause, or that other reasons may prevail. Sometimes this electrical action occurs while 75 the lamp is being burned or during seasoning thereof, but regardless of whatever may be the cause of this electrical phenomenon or when it may occur, it is one of the objects of my invention to substantially prevent 80 such injurious action.

Certain other lamp failures during flashing and seasoning are known as burnouts, which result from a filament burning out in one or more spots throughout its length, thus 90 shortening its life. My invention is also designed to eliminate this detrimental feature.

Still another defect is the collection of the getter material in beads here and there 95 along the filament which results in the formation of hot and cold spots throughout the length of the filament. This condition is productive of improper crystal growth during the recrystallization stage, and since a 100 uniform grain structure produces the strongest filament it is obvious that the irregular formation of the crystals caused by beading greatly weakens the filament. The improved getter material which I employ includes a constituent which prevents 105 the getter material from beading in the manner indicated above.

With the present forms of getters it appears almost impossible to prevent occasional lamps from slumping, that is, suddenly decreasing in candle power during the life of the lamps. The reason why such action occurs is not very well understood. It is, however, very desirable to prevent the lamps from performing in this manner since the users may very readily consider the cause thereof as either carelessness in manufacture or poor quality of materials. The improved getter which I have devised prevents lamps from performing in the manner just mentioned.

It is the purpose of my invention, in view of the foregoing factors, to provide a process for treating metallic filaments, such as are ordinarily employed in lamps, whereby the crystalline formation may be controlled when the lamp is initially lighted, so that a structure or an arrangement of crystals may be obtained which will be productive of a filament having a strength considerably greater than that which can be obtained under present practice.

An additional object of my invention is to provide a getter material which, when employed in practicing my process, will be productive of an electric incandescent lamp of the vacuum and other types having a somewhat increased candle power maintenance, a more consistent performance throughout its life and a filament of increased strength. In other words, the lamp produced according to my process and practiced with the getter discovered by me is more efficient in so far as filament strength is concerned than any commercial lamp heretofore produced.

These objects, as well as other objects, will be apparent from a reading of the following description.

My invention may be briefly stated as comprising a process which consists in controlling within certain limits by means of getter substances, the temperature to which the selected filamentary material is raised upon initial lighting whereby a crystalline growth is produced during the recrystallization stage which is productive of the maximum strength filament after the same has been thus lighted. The getter materials which I find preferable to employ in order to effect the control desired, includes those having high melting point substances, as I have determined with such substances present in the getter a more efficient product may be obtained. Up to the present time the most satisfactory results are obtainable when the melting point of the material added to the getter is approximately equal to the germinative temperature of the selected filamentary material under conditions of a first-class vacuum. The reason for this will be more fully appreciated hereinafter.

By getter substances, I mean such substances which when introduced within the bulb effect an improvement in the quality of the lamp.

Metallographic tests on electric lamp filaments have demonstrated that during the process of flashing a filament, the original drawn structure does not remain, but instead a change or recrystallization occurs during which action the original elongated crystals break-up into a smaller crystalline formation. It is also observed that when these new crystals are of uniform dimensions and of small size and are distributed regularly throughout the length of the filament that the latter is much stronger than when the crystalline formation is irregular, that is, in groups of large crystals intermingled with groups of smaller fine-grained crystals, or even when the crystals are distributed regularly but are relatively large in size. Further, metallurgical investigations have led to the discovery that where filaments are raised to high temperatures the crystalline growth is excessive.

In practicing present processes for flashing the getter substance in the lamps, provision has been made by placing resistance in series with the filament to prevent the current passing through the filament from reaching proportions sufficiently large to detrimentally heat the same. In spite of the precautions taken, however, the filaments become heated to temperatures which are detrimental to the desired crystal growth.

I have discovered that the temperatures to which the filaments are raised during the flashing treatment may be governed by employing substances which will consume a portion of the heat energy which passes through the filament when flashed, so there will be no likelihood of the filament becoming excessively heated. In order to secure the desired action it is preferable to place the substances in thermal conductive relationship to the filament. My experiments have demonstrated that a substance or compound having a high melting point is preferable to those of lower volatilization temperatures although I have proven that the latter also produces increased filament strength upon flashing.

It is preferable that the high-melting point material possesses the property of being substantially inactive with respect to the filamentary material. By substantially inactive I mean that any compounds which may be formed by the combination of such substance and the filament or residual gases, must be of such nature that they do not produce detrimental effects upon the life, quality or candle power maintenance of the lamp. It is preferable to employ only such compounds or substances which are wholly inactive. However, in view of the high

- temperature conditions which exist in electric incandescent lamps, particularly those of the vacuum type, and the high vacuum under which many of these lamps operate, 5 which furnish favorable conditions for unusual or unexpected phenomena, it is impossible to determine whether or not the particular substances, hereinafter more fully identified, are inactive or not.
- 10 In practice it is preferable to add the high melting point substance to any of the well-known getter materials and affix the mixture in any desired manner to the lamp filament.
- 15 It is my belief that the action of the substance added to the getter serves to control the temperature to which the filament may be elevated and that it holds this temperature within certain bounds and at least prevents the temperature from rising to such a degree that detrimental crystal growths progress. Why the added material should operate in the manner indicated is not well understood, but it is possible the action may 20 be that during the transition of the added substance from the liquid or solid state into the vapor condition, the requisite amount of heat or energy required to effect such change, that is, the latent heat of vaporization, is obtained by absorption or otherwise from the filament, thus effecting a reduction in the amount of energy or heat within the filament. It will thus be seen that the compound protects the filaments from high 25 temperatures. Although the above explanation is advanced in support of the action of the added substance it is to be understood that other equally plausible theories may be advanced; therefore, I do not wish to be understood as limiting this invention by any 30 particular explanation made herein.
- During the flashing of lamps which have been treated with a high-melting point substance of the character indicated, it is observed that the customary "blueing" or arcing which occurs when ordinary getters are employed does not result. The reason why the presence of the high-melting point substance, which prevents the occurrence of this 35 phenomena, which latter, as explained above, is frequently injurious to the lamps, is not well understood. It is possible, however, that because of the presence on the filament of the highly refractory compound, ionic emission is suppressed. Furthermore, it is probable that a sufficient quantity of the refractory compound remains on the filament to protect it from the bombardment of positive ions, which, some believe, results in the 40 pitting and, therefore, the weakening of the filament. By reason of the highly refractory compound preventing arcing it has been found feasible to burn lamps treated with such a compound directly on a commercial 45 circuit without previously having been subjected to a flashing treatment, thus indicating the practicability of eliminating that step in the fabrication of electric incandescent lamps.
- The addition of the high-melting point substance to the getter prevents the getter from accumulating in beads along the filament at initial lighting, thus permitting a uniform distribution of that ingredient of the compound which prevents "blackening" of the 50 inner walls of the envelope.
- Having described the broader aspects of my invention, I shall now cite a specific application thereof. My preferred process is to first prepare a getter mixture containing the following active ingredients in approximately the following percentages by weight: silicon oxide 40% cryolite 50% and phosphorus 10%. A homogeneous mixture may be made of these substances and a thin coating thereof may be applied in any desired manner to the filamentary material. The coating may be dried and thereafter the coated filament severed into appropriate 55 lengths and mounted in an incandescent electric lamp envelope in the usual manner. The envelopes may be evacuated and permanently sealed-off. If a gas-filled lamp is being manufactured, the nitrogen, argon or other gas should first be introduced into 60 the envelope prior to sealing-off.
- The lamps thus formed may then be subjected to an initial burning or heating, commonly called flashing, which operation heretofore had a single purpose, namely that of 65 flashing off the getter, but which, with my improved getter, has the additional function of flashing-off the added substance which operates to regulate the temperature to which the filament is raised during the flashing steps. The flashing operation may be conducted in accordance with the present schedules and at approximately the designed voltages and the usual percentages of current. During the flashing operation the phosphorus constituent of the getter being of low 70 vaporization temperature will be the first of the materials to vaporize, and in its vaporized state it combines with the residual gases to eliminate their detrimental effects and to assist in forming a first-class vacuum. The cryolite is next vaporized and functions as the candle power maintenance ingredient. The material of high vaporization temperature, in this case the silicon oxide, is next 75 vaporized and because of the time required to complete its transformation to a vapor state due to its high latent heat of vaporization, the phosphorus and cryolite constituents are enabled to fully complete their respective functions. The high vaporization ingredient also prevents the cryolite and phosphorus from beading along the filament with the result that the filament is heated 80 uniformly throughout its entire length,

thus serving to reduce to a minimum the malformation of crystal growths.

Through tests made under operating conditions I have demonstrated that lamps treated with getters having silicon oxide therein burn at increased efficiencies during the full length of their lives. In addition, I have observed that the length of the life of a lamp may be shortened without affecting its operating efficiency by adding predetermined amounts of silica.

An example of another getter mixture wherein the silicon oxide is substituted by another compound, is one having its active ingredients in the proportions by weight as follows: aluminum oxide 30%, cryolite 60% and phosphorus 10%. Getters which include in regulated amounts other materials of high vaporization temperatures as mentioned above, have been successfully employed, as, for instance, beryllia 15%, cryolite 75% and phosphorus 10%.

Although I have enumerated refractory oxides as the added or heat controlling ingredient, it should be understood, that the use of all refractory compounds which do not detrimentally react with the filamentary material are contemplated by my invention.

Now that I have described my process and the ingredients of the getter, which will be found particularly advantageous in practicing the same, it is to be understood that such modifications as suggest themselves and which fall within the scope of the appended claims are contemplated by my invention.

What is claimed is:

1. The process of controlling the crystal growth in a metal lamp filament when initially heated which consists in coating said filament with a compound having a high volatilization temperature and which will not react detrimentally with said filament or the residual gases within the lamp.
2. The process of controlling the crystal growth in a metal filament of an electric incandescent lamp during flashing which consists in introducing into said lamp on the filament thereof a refractory substance capable of volatilization at the flashing temperature.
3. The process of treating the metal filament of an electric incandescent lamp to effect an increased strength on the filament after flashing, which consists in uniformly distributing over said filament a chemical compound capable of promoting a uniform

temperature condition throughout the length of said filament.

4. The process of controlling the crystal growth in metal filaments during flashing, which consists in preventing the temperature of said filament from substantially exceeding the germinative temperature thereof by applying a heat absorbing medium as a coating to said filament.

5. In an electric incandescent lamp an incandescent metal body having a chemical coating thereon of a high vaporization temperature approximating the germinative temperature of said body.

6. In an electric incandescent lamp an incandescent metallic filament having a refractory oxide getter applied directly to the surface thereof.

7. In an electric incandescent lamp an incandescent metallic filament coated with a refractory oxide, said oxide being incapable of combining with said filament.

8. In an electric incandescent lamp a metal filament having a coating of silicon oxide.

9. In an electric incandescent lamp a metal filament having a getter applied thereto, said getter having a refractory compound as one of its constituent substances.

10. In an electric incandescent lamp a metal filament having a getter composed of cryolite, phosphorus and an inert refractory substance.

11. In an electric incandescent lamp a metal filament having a getter composed of cryolite, phosphorus and a substantially inert compound having a high volatilization temperature.

12. In an electric incandescent lamp a metallic filament having a getter composed of cryolite, phosphorus and silicon oxide.

13. A getter directly applied on an incandescent filament and containing a substantially inert refractory substance.

14. A getter directly applied upon a refractory metal filament and containing silicon oxide.

15. A getter comprising cryolite, phosphorus and a substantially inert refractory oxide.

16. A getter comprising cryolite, phosphorus and silicon oxide.

In testimony whereof, I have hereunto subscribed my name this 2 day of December, 1921.

WILLIAM CHARLES SPROESSER.
